Primary Examiner — Ian Simmons*Assistant Examiner* — Shannon Morgan(74) *Attorney, Agent, or Firm* — Albert W. Watkins(57) **CLAIM**

The ornamental design for a nested tray for cutting and serving melon, as shown and described.

DESCRIPTION

FIG. 1 is a top plan view showing my new design of the nested tray for cutting and serving melon;

FIG. 2 is a front elevational view thereof, with the back elevational view being an identical mirror image thereof;

FIG. 3 is a left side elevational view thereof, the right side elevational view being an identical mirror image thereof;

FIG. 4 is a bottom plan view thereof;

FIG. 5 is an exploded view showing the top and bottom trays separated of the nested tray for cutting and serving melon;

FIG. 6 is a top plan view of the bottom tray of the nested tray for cutting and serving melon showing the top tray removed for ease of illustration of FIG. 1;

FIG. 7 is a top plan view of the top tray showing my new design of the nested tray for cutting and serving melon;

FIG. 8 is a bottom plan view of the top tray of the nested tray for cutting and serving melon thereof;

FIG. 9 is a left side elevational view of the top tray of the nested tray for cutting and serving melon, the right side elevational view being identical thereof; and,

FIG. 10 is a front elevational view of the top tray of the nested tray for cutting and serving melon, the back elevational view being identical thereof.

The broken lines in FIG. 4 of the nested tray for cutting and serving melon are for the purpose of illustrating environment, and form no part of the claimed design.
